UNITED STATES PATENT OFFICE.

ANDREW C. KAPPES, OF CHICAGO, ILLINOIS, ASSIGNOR TO WM. WRIGLEY JR. COMPANY, OF CHICAGO, ILLINOIS, A CORPORATION OF WEST VIRGINIA.

CONFECTION PACKAGE.

Application filed June 18, 1923. Serial No. 645,957.

To all whom it may concern:

Be it known that I, ANDREW C. KAPPES, a citizen of the United States, and a resident of Chicago, in the county of Cook and

5 State of Illinois, have invented certain new and useful Improvements in Confection Packages, of which the following is a specification.

This invention relates to improvements 10 in confection packages, and more particularly to means for and method of packaging a confection in the form of a lozenge or tablet of candy coated chewing gum.

A convenient method of packaging confections of this character is the wrapping of a given number, preferably ten, in a covering or wrapper of waxed paper sealed to exclude moisture, the several pieces being arranged in a row, face to face, throughout the length of the package. In size and shape, as well as exterior appearance, the package thus formed resembles the more common form in which sticks of gum are sold.

In consuming the contents of a package of tablet confections one end of the sealed wrapper is ordinarily opened and the tablets removed as desired, the remainder of the package being carried in the pocket until its contents are entirely consumed.

30 In the packaging of the tablets it is not contemplated that the wrapper shall be applied so tightly as to prevent the tablets from becoming dislodged in the handling of package subsequent to its initial opening, even with the addition of an outer band or label which surrounds the package. As a result there is a tendency for the tablets to become loosened in the wrapper and to escape from the opening at the end.

The object of the invention is to provide a package in which the tablets are held in place within the package with sufficient security to prevent them from falling out in ordinary handling, but permit them to be readily removed, one by one, as they are consumed. The package is preferably provided with the tablet retaining means during the wrapping operation, the method being hereinafter described in connection with the accompanying drawings, in which

Figure 1 is a perspective view of the novel confection package with the outside wrapper removed,

55 Figure 2 is a view in side elevation of a

row of tablets in package form with the wrapper shown in longitudinal section, and

Figure 3 is a perspective view of a single tablet.

As already suggested, the tablets A are wrapped in package form by machines especially designed for the purpose. The material preferably used for the wrapping is a suitable grade of waxed or paraffin paper. The tablets are fed to the machine and in their progress therethrough are arranged in rows and in ultimate package form, each row being successively wrapped and sealed in sheets B of the wrapping material fed to the point of wrapping from a roll and severed therefrom in proper size.

The method of wrapping the contents of a package is one in which the longitudinal margins are overlapped and the end margins tucked in and folded at the ends of the package, as clearly shown in Figure 1. Subsequent to the folding operations the overlapping edges and ends of the wrapper are sealed, this being done by the application of heat, utilizing the paraffin content 80 of the paper as the adhesive substance.

To accomplish the purpose of retaining the individual tablets within the package and to complete the package contemplated by the invention, the following practice is 85 preferably followed: Substantially throughout the length of the package, and extending completely around the package are a plurality of depressions or grooves b. These depressions are located between the tablets A, their edges being rounded so that natural depressions or spaces are formed into which the material can be depressed. Moreover, these grooves or depressions are comparatively permanent, at least during the time 90 occupied by the consumption of the package, the permanency being due to the nature of the material used and the paraffin content with which it is impregnated. For this reason the application of heat is suggested 95 as the means for introducing the grooves into the package, this being capable of accomplishment in several ways, but preferably by passing the packages through or between plates or dies having the grooved 100 formation, and maintained at a temperature sufficient to soften the paraffin. Having thus been grooved or depressed the subsequent cooling causes the material to set and thereby maintain the grooved or corrugated con-

110

- tour of the package. Moreover the application of heat causes a bond to be formed between the material of the wrapper and the edges of the tablets by reason of the adhesion of the paraffin in the paper to the edge surfaces of the tablets.
- Thus it will be seen that the several tablets are lodged between the depressions or grooves *b* with the intermediate portions of the material fitting around and adhering to the edges thereof. In this manner each tablet is retained in an individual compartment and thus held in place, without dependence upon the adjacent tablets for support against displacement. Hence the removal of the tablets from one end or the other does not disturb the remaining tablets, to the end that the package and its contents remain intact until entirely consumed.
- 20 While the corrugations or grooves may be extended throughout the entire length of the package it is manifestly unnecessary to treat the ends of the package since the end tablets would ordinarily be removed when the package is opened. Thus in the package disclosed the formation of the grooves includes only the tablets intermediate the ends. As is the usual practice, the sealed package or wrapper is surrounded by a band or label, thus concealing the grooves beneath.
- 25 I claim as my invention—
1. A package for confections consisting of a wrapper enclosing a plurality of tablets arranged face to face in package form, the material of said wrapper being depressed into the spaces separating the tablets and extending transversely of the sides of said package.
2. A confection package consisting of an enclosure for a plurality of tablets having rounded edges and arranged face to face in package form, and depressions formed around said enclosure and conforming substantially to the spaces separating the edges of said tablets.
3. A method of packaging confection tablets having rounded edges consisting of wrapping said tablets face to face in a sealed paraffin wrapper and subjecting said package to pressure in the presence of heat, whereby said wrapper is set with substantial permanence to conform to the surface contour of the tablets.
4. A method of packaging confection tablets consisting of wrapping the tablets in a wrapper of paraffined paper, sealing the wrapper by the application of heat, and subjecting said package to pressure between heated dies acting to form in said package a series of depressions extending around the package and between the edges of said tablets.

In witness whereof, I hereunto subscribe my name this 11th day of June, A. D. 1923.

ANDREW C. KAPPES.
